Primary Examiner — Jonathan J Han

(74) *Attorney, Agent, or Firm* — Banner & Witcoff, Ltd.

(57) **CLAIM**

The ornamental design for a shoe, as shown and described.

DESCRIPTION

FIG. 1 is a side view of a shoe showing my new design;
FIG. 2 is a rear perspective view thereof;
FIG. 3 is a rear view thereof;
FIG. 4 is an opposite side rear perspective view thereof; and,
FIG. 5 is an opposite side view thereof.
The broken lines immediately adjacent to the shaded area
define the bounds of the claimed design and form no part
thereof. The broken lines depicting the remainder of the shoe
form no part of the claimed design.

1 Claim, 5 Drawing Sheets
